SOUND-REPRODUCING APPARATUS.

Application filed October 1, 1926. Serial No. 138,882.

The present invention relates to sound reproducing apparatus for use in radio receiving sets, phonographs, and the like, and has to do with the conversion of energy from one form to another and particularly with the conversion into sound of the impulses of electrical energy which occur in the apparatus and which represent the sounds being reproduced.

10 Radio receiving sets, for example, are designed to receive or "detect" incoming impulses of electrical energy representing sounds, which impulses proceed from the transmitting station, and to pass such impulses into a device capable of translating or converting them back into sounds which are intended to duplicate and thus reproduce the original sounds generated for transmission. The relatively feeble incoming impulses are commonly amplified in the radio receiving set by means of vacuum tubes or the like before being passed to the part of the apparatus which converts them into sound to thus facilitate the generation 20 of sound in sufficient volume to be conveniently heard and enjoyed by the listener. The device for converting the impulses of electrical energy into sound may assume various forms, as, for instance, ordinary telephone receivers introduced into the electrical circuits of the apparatus at the proper point and applied to the ear of the listener, the ordinary type of "loud speaker" which is intended to radiate a volume of sound 30 sufficient to conveniently be heard throughout a room, or the like. The quality of the reproduction depends upon the accurate conversion of the original sounds into the form of electrical impulses and the proper transmission of such impulses as well as upon the accurate reception and conversion of the transmitted impulses into sounds. The present invention has to do with the last mentioned step in this process of modifying 40 and converting energy from one form to another, namely, the conversion of the impulses of electrical energy in the receiving apparatus into sound.

It is an important object of the present 50 invention to provide a sound reproducing device or unit of the class just referred to which converts the impulses of electrical energy occurring in the receiving apparatus into sound more accurately than is possible in apparatus of this general class as hereto-

fore proposed, to thus reproduce the original sounds more faithfully and naturally in all of their qualities. Distortion or poor quality in the reproduced sounds, which originates in the sound producing unit, 60 arises principally from two causes. The first of these causes is the failure of the apparatus to handle and reproduce sounds of different pitch in an identical manner. If, for instance, an apparatus freely handles 65 and satisfactorily reproduces the higher frequencies, that is, sounds of relatively high pitch, but does not freely handle the lower frequencies but rather offers a resistance to their passage through the apparatus and 70 thus reproduces the lower sounds to a lesser extent than it does the sounds of higher pitch, the result is that the reproduction of the original sounds is not accurate. The deficiency in the low tones produces an unbalanced and an unnatural effect in the reproduced sound which greatly impairs the quality of the production. The second of these causes is the introduction into the reproduced sounds of additional frequencies 75 or harmonics or of additional quantities of frequencies or harmonics already present. Harmonics are sounds of frequencies which are multiples of the frequencies occurring in the original sounds intended to be introduced. The effect of the introduction of these harmonics is principally a change in the quality of the sounds which renders the reproduced sounds to a certain extent unlike the original. The apparatus of the present 80 invention converts the electrical impulses into sound in such manner that all frequencies are converted and reproduced more nearly to the same extent and with a lesser introduction of undesirable harmonics than 85 has been heretofore accomplished. If the electrical impulses in the receiving apparatus fairly represent the original sounds, the present apparatus continues the reproduction satisfactorily and produces as its 90 ultimate result sounds which in a fair sense duplicate the original sounds intended to be reproduced.

It is a further object of the present invention to provide a sound reproducing apparatus of the class described which is of maximum efficiency; that is, an apparatus which will produce a maximum sound output for a given power input as determined by the electrical energy supplied to it from 100 110

the receiving apparatus. One important practical result of this is that a satisfactorily loud reproduction may be obtained with the use of a lower electric current in the output circuit of the vacuum tubes of the radio set. An excessive output current often results in "over-loading" of the vacuum tubes, particularly the tube which constitutes the last stage of the audio frequency amplifier, with the result that an unpleasant scratching noise and confusion of sounds is introduced into the reproduced matter.

It is a still further object of the present invention to provide a sound reproducing unit of the class described which is of rugged and compact construction, is capable of handling a large amount of energy and is designed throughout in every detail of mechanical and electrical structure to attain the results above noted. The invention, therefore, contemplates all of the various novel features of electrical and structural design which function to accomplish the improved reproduction which is effected by the apparatus.

A preferred embodiment of the invention is shown in the accompanying drawings in which Figure 1 is a side view of the apparatus with the main portion of the housing removed; Figures 2 and 3 are end views taken from the left and right ends, respectively, of Figure 1; Figure 4 is a view generally similar to Figure 1 taken from the opposite side of the apparatus; Figure 5 is a transverse sectional view taken on line 5—5 of Figure 4; Figure 6 is a longitudinal sectional view taken on line 6—6 of Figure 3; Figures 7 and 8 are sectional views of structural parts of the unit taken on lines 7—7 and 8—8, respectively, of Figure 6; and Figures 9 to 15 are views showing structural details of the apparatus.

A principal use of the apparatus of the present invention is the conversion of impulses of electrical energy into sound, and in such a function the apparatus is essentially an electric motor energized by these impulses of electrical energy which are present in the receiving apparatus and which serve to drive or vibrate correspondingly a suitable sound radiator or diaphragm to thus generate the sound. In common with certain apparatus of this same general class which has been used heretofore, the present unit is a driving motor of the balanced armature type wherein an armature of a magnetic material is suspended between the poles of a magnet and is caused to move in that space in a manner which bears a definite relation to the incoming impulses of electrical energy which actuate it and which represent the sounds intended to be reproduced. The moving armature is connected with the sound radiating diaphragm and thus serves to vibrate the diaphragm in a definite man-

ner to thereby generate sounds the character of which are determined by the manner in which the driving armature is actuated by the incoming signals.

The parts of the unit are supported principally from a main frame member 1, which in turn is secured to the cover 2 of the apparatus housing 3 so that when the cover 2 is removed from the housing 3 the entire working mechanism of the apparatus is withdrawn from the housing as a unit. The cover 2 is provided with a hollow extension portion or throat 4 upon which the usual sound amplifying horn may be mounted. Covering the inner end of the throat portion 4 is the sound radiating diaphragm 5 which is driven by the unit enclosed within the housing 3 and which serves to generate the sounds which are radiated from the apparatus. The present unit is adaptable to the driving of any of the well-known types of sound radiators and is not in any sense restricted in its application to the use of the amplifying horn. In applying the unit to other types of sound radiators the structural details of the enclosing housing and the mounting of the unit are appropriately modified, but the essential structure of the operating parts of the unit remains unchanged. For example, in applying the unit to the cone type of sound radiator, the entire unit may most conveniently be housed within the cone, and the cone itself is the radiating diaphragm which is driven by the unit and which corresponds to the diaphragm 5 in the structure here shown.

The main frame portion 1 supports the permanent magnet 6 whose function is to provide the permanent magnetic field requisite to the operation of the apparatus. For operational and manufacturing reasons a permanent magnet is usually preferable to an electromagnet for this purpose.

The opposite arms of the magnet are provided with suitable pole pieces 7 and 8. Each of the pole pieces 7 and 8 is divided to form pairs of arms 9, 10 and 11, 12, respectively, which extend into proximity with each other as shown in Figure 6. The pole faces, therefore, consist of the adjacent faces of the divided portions or arms of the pole pieces 7 and 8. In the gap between the pole pieces is suspended an armature 13 of magnetic material. The armature derives its support from a pair of flat spring members 14 and 15 which extend in a plane parallel to the length of the magnetic pole pieces 7 and 8, which lie substantially centrally of the open spaces between the arms 9 and 10 and the arms 11 and 12 of the respective pole pieces and which have their center lines substantially coincident with the center line of the air gap between the adjacent pole faces, as shown in Figures 5 to 7. The respective spring members

14 and 15 are secured at their outer ends to the frame member 1, as indicated at 16 and 17, respectively, and their inner ends are slotted to fit over and support the armature 13 in the manner indicated at 18. Thus the armature 13 is supported rigidly against bodily movement in the direction of the length of the pole pieces 7 and 8 and is tiltable in the air gap between the 10 pole faces of the magnet. Such tilting movement of the armature is opposed by a twisting flexure of the springs 14 and 15, the springs serving to normally hold the armature in its neutral position centrally 15 disposed in the air gap between the adjacent pole faces of the magnet and extending in a direction parallel to the center lines of the air gap so that it is equidistant from each of the four pole faces at the ends 20 of the arms 9, 10, and 11, 12. The armature 13 is connected to the driving rod 19 which also has an attachment with the sound radiating diaphragm 5. Movement of armature 13 is therefore transmitted to 25 the diaphragm 5, with the result that movements of the armature are converted into sound waves which emanate from the diaphragm. The actuating coils 20 which carry the electric current constituting the 30 impulses of electrical energy supplied to the unit are mounted, as shown, in such manner that they surround the armature 13 as a core and extend through the spaces between the arms of the pole pieces 7 and 8 on opposite sides of the springs 14 and 15. 35 The permanent magnet 6 provides at all times a magnetic field in the gap between the pole pieces 7 and 8 in which the armature 13 is suspended. With the armature 13 balanced in the center of the air gap it is 40 equally distant from all of the pole faces of the magnet, and the pole structure is symmetrical on the two sides of the armature so that the magnetic field established by the 45 permanent magnet does not tend to tilt the armature 13 out of its neutral position. In operation, the binding posts 21 are connected to the output circuit of the receiving apparatus, as, for example, to the output circuit 50 of the vacuum tube which constitutes the last stage of audio frequency amplification in a radio receiving set so that the electric current from the receiving apparatus, which current embodies the impulses of electrical 55 energy which represent the sounds intended to be reproduced, traverses the coils 20 which are in electrical connection with the binding posts 21. When an electric current flows in the coils 20 the armature 13 becomes magnetized to a degree depending upon the magnitude of the current. The armature 13 is in effect a core for the coils 20 and therefore, at any instant when a current flows in a given direction through the coils, it is magnetized definitely with one end constituting 60 a north pole and the other end constituting a south pole. The two coils 20 are wound so that the magnetic effect produced by each coil is in the same direction as that produced by the other. A reversal of the direction 70 of the current in the coils 20 serves to reverse the direction of magnetism in the armature. Referring to Figure 6, if the current in the coils 20 is such as to magnetize the armature 13 with opposite magnetic 75 poles at its respective ends, as indicated by the letters N and S on the drawing, and if the pole piece 7 of the permanent magnet is a north pole and if the pole piece 8 is a south pole the armature 13 will be tilted out of 80 its neutral position in a counter clockwise direction as viewed in Figure 6, with a resulting flexure of the springs 14 and 15. The coils 20 are spaced apart a sufficient 85 distance so that the springs 14 and 15 are free to flex to any degree attained in the normal operation of the apparatus without contacting with the coils. The tilting of the armature takes place about an axis which 90 passes through the armature at the points where it is supported by the springs and which is designed to occur at the geometrical center of the magnetic structure so that the entire pole piece structure is symmetrical with respect to the axis. This tilting movement 95 of the armature 13 may be explained by the fact that when the armature is magnetized with north and south poles located as indicated on the drawing, the north pole N of the armature is repelled away from the 100 north pole face 9 of the pole piece 7 and is attracted toward the south pole face 11 of the pole piece 8. Similarly the south pole S of the armature 13 is repelled from the south pole face 12 of the pole piece 8 and is 105 attracted toward the north pole face 10 of the pole piece 7. Thus the magnetic forces exerted on the armature 13 at both sides of its axis tend to produce a rotation or tilting of the armature in the same direction 110 around the axis. The springs 14 and 15 are of such strength that, when the armature is tilted out of its neutral position, they about offset the pull of the permanent magnet which tends to increase the tilt of the 115 armature, and thus in effect leave the armature free to vibrate under the influence of the current traversing coils 20 so that its movement due to this current is not restrained by forces applied to the armature. 120 The extent of the movement of the armature is limited principally by its own mass. This freedom of movement of the armature is particularly important at low frequencies in order that armature vibrations of sufficiently 125 large amplitude may be produced. The output current of the receiving apparatus which is supplied to the coils 20 varies in magnitude and character depending upon the sounds which are being reproduced and

which that current represents. As the current varies in magnitude, the armature 13 tilts to a correspondingly varying extent. When the current changes direction the armature tilts in the opposite direction because an opposite magnetism is established in it. The result is that the armature assumes a continuous movement about its axis 21 which movement bears a definite relation to the 10 impulses of electrical energy entering coils 20 and which correspond to the sounds being reproduced, so that the armature serves to drive the sound radiator 5 in such manner as to generate sounds which bear a definite 15 relation to the original sounds as represented by the current impulses traversing the coils 20.

In the features just described and in principle of operation the present apparatus is 20 similar to the balanced armature type of driving unit of this general class which has been used heretofore. The present invention has to do particularly with improvements in apparatus of this general class, 25 as, for instance, in efficiency, quality of reproduction, and the like, which improvements are effected chiefly by improvements in the electrical and structural design of the apparatus, improvements in the manufacture 30 of the unit, and the like. Therefore, the physical embodiment of the invention essentially involves these improved features of structure and design, and it is principally in such features that the present unit 35 differs from generally similar units heretofore produced and it is in terms of such features that the physical embodiment of the present invention must, for the most part, be described.

40 The main frame member 1 of the unit is a single unitary member of a bakelite composition, or similar moldable material, which is molded as a single piece at one operation with the pole pieces 7 and 8 in place so that 45 the finished unit consists of the entire frame member 1 with the pole pieces 7 and 8 rigidly secured into and essentially constituting an integral part of the piece. The pole pieces 7 and 8 are laminated as shown according 50 to the usual practice of constructing magnetic part of this nature, and the laminations are held together by rivets 22 which project at the sides of the pole pieces as shown and in the molding process become 55 imbedded in the material of the molded frame member 1 so that they function as retaining means for holding the pole pieces rigidly in fixed relation to each other. To further assist in securing the pole pieces to 60 the molded frame member 1 holes 22^a may be drilled in the outer members or face plates of the pole piece so that, in molding, the material of member 1 will flow into the holes and thus afford an additional connection 65 between the parts. In order that

properly operating units be produced in the course of ordinary manufacture it is necessary that the air gap between the pole faces be accurately obtained and maintained uniform throughout a manufacturing run. 70 When the molded units are withdrawn from the mold they are still hot, and upon cooling material of the member 1 shrinks. Thus when the unit is first withdrawn from the mold the air gap between the pole faces is somewhat greater than it will be after the article has cooled and the resulting shrinkage takes place. The proper air gap is secured by spacing the pole pieces in the mold slightly further apart than they should be in the finished article and providing a gage of thickness equal to the desired width of the air gap which gage is introduced between the pole pieces 7 and 8 when the hot unit is withdrawn from the mold. 80 Cooling of the material causes the pole pieces to shrink down upon the gage and thus, when the article is thoroughly cooled, the pole pieces have been positively set in exactly the position which produces a proper air gap. However, reasonably good results in the spacing of the pole faces 7 and 8 may be obtained without the use of the gage for the reason that in a standardized process of manufacture the shrinkage 85 is always substantially the same and a proper allowance for this shrinkage may be determined upon and provided for when the pole pieces are located in the mold. With this process of manufacture wherein the pole pieces are molded directly into the material of the member 1 and particularly where the pole pieces are shrunk onto a gage to positively determine the width of the air gap, the spacing of the pole pieces is always sure 90 to be correct as a matter of course without necessity of skilled labor and without resorting to a time consuming process of adjustment. This is in contrast to the usual type of structure wherein if any attempt at 95 all is made to obtain a proper air gap and a proper relation of poles, elaborate adjustments are provided to effect relative movement of the pole pieces in all dimensions. Such adjustments while necessary in the structures heretofore employed, add materially to the complicity and cost of the unit, give rise to the danger that the unit will get 100 out of order during use through shifting of the adjustments and introduce an expensive element of labor cost in putting each unit into proper adjustment before it is in condition to be distributed to the trade.

The respective arms of the permanent magnet 6 lie adjacent the respective pole pieces 7 and 8, as indicated at 23 and 24. A close and regular contact between the main body of the magnet and the laminated pole pieces 7 and 8 is required in order to establish a good magnetic circuit. The faces 125

- of contact 23 and 24 between the arms of the magnet 6 and the pole pieces are at right angles to each other. In assembling the unit the magnet is slid into the position shown in contact with the pole pieces and is guided and supported by the recesses in the molded member 1 into which it fits in the manner shown in the drawings. The faces 23 and 24 of the magnet which are to contact with the pole pieces are ground to a fit, the only requirement being that the faces be at right angles with each other. This is in contrast to a structure where, for instance, the parallel end faces of the arms of the permanent magnet come into contact with the pole faces, in which case it is not only necessary that the contacting faces be ground to the proper angle but also that the arms of the magnet be of exactly the proper length. The structure of the present apparatus employing the non-parallel magnet faces simplifies the construction and reduces the manufacturing cost for the reason that it minimizes the number of manufacturing requirements which must be satisfied in order to produce a unit of good quality.
- The springs 14 and 15 which support the armature 13 in the air gap between the pole pieces 7 and 8 are secured to and supported from molded frame member 1 by clamps or connections indicated at 16 and 17. The clamp 16 rests against a flat portion of the member 1, as shown, so that it holds the spring 14 in fixed position. Clamp 17, however, rests upon a projecting portion 25 of the member 1 so that by rocking the clamp across the top of the portion 25 the spring 15 may be turned to thus change the angle of tilt of the armature 13 in the air gap. This furnishes a convenient and speedy adjustment for locating the armature in its proper central position within the air gap. The proper location of the central axis of the armature is accomplished by the use of spacers, as in the ordinary manufacture of apparatus of this general class, and by the provision in the springs of screw holes somewhat larger than the retaining screws so that the springs and armature can be shifted a small amount. Lock washers are provided on the screws so that their position of adjustment is maintained. The adjustment for regulating the tilt of the armature is conveniently effected by means of the two screws 26 which may be independently adjusted to bring the armature into its desired position. This is in contrast to the usual adjustments for the armature, frequently involving a bodily shifting of the armature, which are provided on apparatus of this type. Such adjustments complicate the apparatus and require a considerable amount of time and care in assembly. Furthermore, in practice it has been found possible to provide for but a small range of adjustment. Frequently

this range is insufficient to effect a proper adjustment, and in ordinary manufacturing practice the worker often deliberately stresses the supporting springs beyond their elastic limit by twisting them to thus permanently deform them into such position that the armature will lie properly in the air gap. Such treatment, of course, destroys the characteristics of the springs. The present invention provides practically an unlimited range of adjustment for the armature without necessity of flexing or bending the springs to any damaging extent.

The springs 14 and 15 are preferably tapered as shown so that their outer ends are wider than their inner ends which engage the armature. This shaping makes for stiffness and affords a high degree of rigidity which prevents movement of the armature bodily toward either one of the pole pieces 7 or 8. At their inner ends springs 14 and 15 are slotted so that they fit over the armature 13 for a considerable distance, as indicated at 18. The armature 13 is flat and wide so that a large region of contact between the slotted springs and the armature is provided. This contact is sufficiently extensive so that a supporting connection of adequate strength between the springs and the armature may be formed by the use of solder of low melting temperature. The heat of soldering is so limited that it does not damage the specially hardened metal of the springs or impair the magnetic properties of the armature, and therefore the character and properties of the springs and armatures are the same after the apparatus is completely assembled as they were at the time the parts were made. Thus the springs can be made up originally of exactly the proper strength and stiffness, and they may be so designed that a wide range of tilt of the armature is possible without stressing the metal of the springs beyond its elastic limit. The possibility of making up initially springs of exactly the proper qualities, the fact that the spring are not injured during the manufacture of the unit and the fact that a wide range of tilt of the armature is possible with such springs without injuring them all make for a proper response and control of the armature and a correspondingly increased excellence of reproduction. Heretofore, where this type of spring support was used a relatively narrow armature was ordinarily employed, usually being fairly thick. The narrow width of the armature restricts the amount of contact which can be effected with the supporting springs, with the result that in order to effect a connection of sufficient strength it is necessary to employ a high melting temperature solder. During the soldering process the high temperatures attained soften

the metal of the springs. With the metal thus softened a lesser stress is required to deform the metal beyond its elastic limit, and such stress will permanently deform the metal. Hence, if the springs used in the manufacture of the apparatus are initially of the proper strength they become so softened and weakened by the heat of the soldering process that stresses which 10 the original springs would have satisfactorily withstood and which are normally attained in the operation of the apparatus are of sufficient magnitude to stress the springs beyond their elastic limit, thus permanently deforming them and rendering the operation of the apparatus generally unsatisfactory. Accordingly, the general practice is to use springs which are originally too stiff so that after the soldering 20 process they will still be of sufficient strength to be serviceable. The soldering operation on different units affects the springs to different degrees and hence no particular uniformity in the product can 25 be expected. The present invention eliminates these difficulties and makes possible the provision in each apparatus of springs and armatures having known correct properties which are uniform throughout a 30 manufacturing run.

The armature 13 is wide and short. By the length of the armature is meant that dimension of the armature which is perpendicular to the plane of the coils 20 and by 35 the width of the armature is meant the other principal dimension of the armature which extends at right angles to its length. Being wide the armature can be thin and still present a substantial cross section 40 area. It is important that the armature be of considerable width and of relatively little thickness, whereby it more nearly approximates in appearance a flat sheet than a block or body of any considerable thickness. This shaping of the armature is particularly important in the matter of 45 restricting power loss in the apparatus and of preventing distortion of the reproduced sounds. The changing magnetic flux produced in the iron core of a coil which is 50 carrying a varying current, as are coils 20, induces electric currents in the metal of the core. These induced currents, or eddy currents, flow in closed paths which encircle 55 the axis of the coil and which are generated in planes that are parallel to the plane of the coil, that is, perpendicular to the direction in which the magnetic flux passes through the core. Looking at a section of 60 the armature taken parallel to the plane of the coils, as in Figure 5, the armature appears as an elongated strip, and it may be seen that the average closed path encircling the central axis of the armature and coils 65 is of much greater length than would be the case if the armature were more nearly square in cross section. This long path introduces a correspondingly high electrical resistance opposing the flow of the induced eddy currents and thus reduces in direct 70 proportion the amount of these undesirable currents. This feature of the present invention, therefore, reduces the power loss in the apparatus and consequently improves its efficiency. The losses resulting from these 75 eddy currents are more pronounced with currents of the higher frequencies, and therefore the presence of such losses restricts the passage of the high frequencies through the apparatus to a greater extent 80 than it does the lower frequencies and consequently produces an unbalancing or distortion in the ultimate sounds produced by the apparatus. To overcome this difficulty it has been proposed to laminate the armature, but such an expedient is not successful due to the fact that it adds to the manufacturing cost of the apparatus and due to the fact that a composite armature structure 85 will not satisfactorily vibrate at high frequencies as an integral unit. The short length of the armature also correspondingly reduces the loss and distortion arising out of undesirable currents induced in the armature. These difficulties incident upon the 90 armature. These difficulties incident upon the induced currents are directly proportional to the length of the armature for the reason that the currents flow in planes which are perpendicular to the length of the armature and the width of the current path is therefore the length of the armature. By shortening the armature and thus reducing the width of the current path the conducting 95 property of the armature with respect to these currents is reduced in the same proportion. Furthermore, the minimizing of the length of the armature limits its mass and brings nearer to its axis of rotation the average mass of each of the two halves of 100 the armature which lie on opposite sides of the axis with the result that the armature, particularly at the higher frequencies, vibrates more nearly in exact response to the varying current traversing the coils 20.

The present structure employs a relation 115 between the transverse cross sectional area of the armature and the area of the pole faces which is radically different from that heretofore employed in apparatus of this general class. For the best results, a high 120 magnetic flux density should be maintained in the metal of the pole faces for the reason that with such a high flux density a given current in the actuating coils 20, through the medium of the resulting magnetic flux generated in the armature, produces a greater 125 movement of the armature and of the diaphragm 5 with the production of a correspondingly greater volume of sound. The magnetic circuit should be so designed that 130

the pole pieces just reach the saturation point when they are carrying the maximum amount of magnetic flux which the apparatus demands. The arms 9, 10, and 11, 12 which constitute the pole faces are tapered, as indicated at 28, to concentrate the permanent magnetic flux in the air gap and to aid in effecting a uniform distribution of magnetic flux throughout the pole faces. The actual size of the pole faces depends upon the amount of power which the apparatus is required to handle, but by using an appropriately high flux density at the pole faces a maximum amount of power per unit of pole face area may be obtained from the device. I have found that in apparatus of this general class heretofore proposed serious difficulty arises because of the fact that the magnetic flux density in the armature invariably reaches the saturation value at relatively slight positions of tilt of the armature out of its normal neutral position. As the armature tilts its respective ends approach more closely to the respective pole pieces 7 and 8 with the result that an increased amount of magnetic flux traverses the armature. Saturation of the armature at degrees of tilt frequently attained in the normal operation of the apparatus introduces harmonics into the sound output of the apparatus and consequently produces a distortion of the reproduced sound. Furthermore, when this condition of saturation in the material of the armature exists, a given power input to the apparatus produces a lesser tilting of the armature with the result that a larger power input for a given sound output is required. As a corollary to this proposition a larger power input is required to effect a given tilt and consequently a given sound output, with the result that in order to obtain a satisfactory sound output the amplifying tubes are often required to handle a larger amount of power than can be done satisfactorily so that over-loading of the tubes and distortion of the reproduced sound results. This is particularly the case for the lower frequencies. In the present invention the cross section of the armature is preferably substantially equal to the area of each of the pole faces provided on the arms 9, 10, 11 and 12. Fairly good results may be obtained with an armature cross section of somewhat less than this amount, but for the best results the ratio of pole face area to armature cross section should be approximately unity. In the structure here shown the armature may tilt practically as far as the mechanism of the apparatus allows without passing the saturation point. The result is that an improved quality of reproduction is effected and a large sound volume output is obtained for a given power input. The sound radiating diaphragm 5 may assume any appropriate form, as, for in-

stance, a flat diaphragm, a cone or the like. It is here shown as a cone ribbed along its surface as indicated at 29 and provided at the open end of the cone with an integral flat disc portion 30 having formed in it circumferential corrugations 31. The ribs 29 add rigidity to the cone portion of the diaphragm while the corrugations 31 in the disc portion 30, which is secured as indicated at 32 to the cover plate 2, afford a flexibility of the unit which permits the rigid cone portion to vibrate bodily as a rigid unit, all of the flexure of the diaphragm 5 occurring in the flat disc portion 30.

A single driving rod 19 connects the armature 13 directly with the sound radiating diaphragm 5. This direct drive is possible due to the fact that, as above described, the armature 13 has a wide range of tilting movement in the air gap and thus vibrations of sufficiently large magnitude are imparted to the diaphragm 5 by the direct drive. This avoids the mechanical linkage or extended portion on the armature frequently employed in the driving connection between the armature and the diaphragm because of the fact that the amplitude of movement of the armature is so small that its motion must be magnified in order that it will impart a sufficient movement to the diaphragm. Such connections introduce frictional loss or transition loss due to improper loading of the driving unit and add to the mass of the moving parts with the result that, particularly with high frequencies, the reproduction becomes inaccurate. I have found that important advantages are obtainable by employing a hollow thin walled tube as a driving element. This is in contrast to the usual solid metal rod. This hollow tube driving element affords a greater stiffness and resistance to bending than does a solid rod embodying the same weight of material. The driving element 19 of the present structure is of less weight than the usual solid rod employed in units of this general class and at the same time is stiffer and affords a more positive and rigid drive without sidewise vibration. The reduction in mass aids in giving to the apparatus a more delicate response particularly at the higher frequencies, and the strength and rigidity of the drive avoid the introduction of undesirable qualities in the reproduced sound due to sidewise vibration of the driving linkage, and the like. With the usual solid driving rod much difficulty is encountered in breaking of the rod or the solder joint at the point where the rod is connected to the armature. As the armature tilts and actuates the diaphragm through the medium of the rod a certain flexure of the rod is produced, and in the ordinary structure this bending action tends to break the rod near its end adjacent the armature or to break open the solder

joint between the rod and the armature. In the present apparatus the upper end of the rod 19 is flattened for a short distance as indicated at 33. This serves to provide a 5 large area of contact between the rod and the armature and thus permits a very substantial solder joint. Also, the flattened upper end of the rod is in effect a thin strip of material and readily takes up the 10 bending action which the rod must absorb during operation of the apparatus without concentrating the bending stress on the solder joint or on any particular point in the rod to such extent that breakage will occur. 15 The flattened portion of the rod extends throughout only a small portion of the length of the rod and is furthermore removed from the middle of the length of the rod so that no objectionable sidewise vibration or lack of stiffness is introduced because of this feature. The end of the driving rod 19 which is adjacent the diaphragm 5 is passed through a hole at the apex of the cone portion of the diaphragm and its end 20 portion which extends within the cone is flared out so that the metal of the tube lays against the inner face of the diaphragm over a substantial area as indicated. With this 25 large area of contact between the end of the driving tube 19 and the diaphragm 5 a substantial joint is effected by merely dropping a small quantity of an appropriate wax over the flared end of the tube, as indicated at 40. This avoids the inconvenient and complicated 30 threaded nut and washer connection which is ordinarily employed with the usual solid rod driving element, and thus further reduces the mass of the moving parts. 35

The apparatus of the present invention is 40 also operable as a generator of electrical energy. For example, in phonographic reproduction from the usual permanent grooved record the present apparatus may be used as a reproducer. The armature of 45 the apparatus is placed in physical connection with the stylus which follows the grooves in the record, and the motion derived by the stylus in passing over the impressions on the record is imparted to the 50 armature. The resulting movement of the armature in the permanent magnetic field of the apparatus generates a changing magnetic flux in the armature, and such changing flux generates a correspondingly varying 55 current in the electric current conducting coils surrounding the armature so that the current in the coils thus bears a definite relation to the impressions on the phonograph record over which the stylus has 60 passed. The present apparatus is particularly well adapted to this use for the reason that its structure and operating characteristics, such as the kind of armature employed, and the like, make possible the attachment 65 of the armature directly to the stylus with-

out the interposition of a mechanical linkage or its equivalent as is necessary in this general class of apparatus heretofore used. The varying current generated in the current conducted winding may be amplified by 70 vacuum tubes in the usual manner and the amplified current then converted into sound by passing it into a second unit which acts as a driving unit for a sound radiating diaphragm in the manner described. Another 75 example of the use of the present apparatus for generator action is as a transmitter. The sounds to be transmitted, as for instance speech, are generated adjacent the diaphragm of the apparatus which is thus 80 vibrated in a manner dependent upon the character of the sounds. The vibration of the diaphragm serves to vibrate the armature with the result that a current is generated in the coils, which current may be conducted over wires to any desired point and then reconverted into sound by passing it 85 into a second unit in the manner described.

The present invention therefore provides a sound reproducing apparatus, and more 90 particularly a unit for converting energy furnished to the unit into a different form, which, in operation exhibits certain advantages over existing units of the same general class, notably an improved quality of 95 reproduction and an improved efficiency, as, for instance, in the matter of volume of sound output derived from a given power input. For the most part these advantages are achieved by improvements in design, 100 both as to the mechanical structure and as to the electrical properties of the unit. The structure permits of easy and inexpensive manufacture and affords a compact rugged high power unit. The whole structure permits of manufacture to close limits as 105 regards the ultimate sound reproducing qualities of the device without, however, requiring other than simple and rapid manufacturing and assembling operations. The 110 manner in which the main frame member of the unit is molded with the pole pieces in place insures by a quick and easy method of manufacture a proper air gap in each unit of a manufacturing run. The construction and manner of fitting the permanent magnet to the pole insures a proper 115 magnetic circuit at a very low manufacturing cost. The structure of the armature and its connection to its supporting springs 120 insures a proper and extensive spring action throughout the entire wide range of movement of the armature, while the adjustment for locating the position of the armature affords a quick and ready means 125 for getting the unit into proper adjustment without injuring any of the parts. The magnetic structure of the armature restricts power losses and distortion. The magnetic structure of the pole pieces and the provi- 130

sion of a proper relation between the magnetic properties of the armature and of the pole pieces effects an improved efficiency and an improved quality of reproduction together with the other advantages that these features imply, as, for instance, the ability to obtain a satisfactory sound volume without recourse to power supply sets and power tubes, and the like. The wide amplitude of movement of the armature permits of a direct drive of the sound radiating diaphragm, and the type of driving connection employed offers improvements in quality of reproduction, ease of manufacture and durability and ruggedness of the unit. The invention contemplates these various improvements of structure and design and the claims are, for the most part, necessarily worded in terms of these features. The invention broadly contemplates the apparatus in so far as it may be characterized by its improved manufacture and operation and by the structural features which make possible these improvements.

25 I claim:

1. Sound reproducing apparatus of the class described which comprises means for producing a magnetic field, a tiltable armature mounted in said field for vibrational movement at sound frequencies, an electric current conducting winding in energy transferring relation with said movable armature, a sound radiating diaphragm, a hollow rod connecting said armature with the diaphragm to thereby vibrate the said diaphragm in definite relation to the movement of the armature, a flared portion at that end of the hollow rod which connects with said diaphragm for presenting an extended area of the material of the rod in contact with the diaphragm, and a connection between the said rod and the diaphragm which consists of a solidified mass of a low melting temperature cementing material covering the flared portion of the rod and the adjacent material of the diaphragm.

2. Sound reproducing apparatus of the class described which comprises means for producing a permanent magnetic field, an armature mounted for tilting movement in said magnetic field and adapted in regular operation of the apparatus to assume a vibrational tilting movement at sound frequencies, an energizing electric current conducting winding in energy transferring relation with said armature for carrying an electric current which by induction energizes said armature and effects a movement thereof which bears a definite relation to the character of the current traversing the said winding, a sound radiating diaphragm, a thin walled hollow rod connecting the armature with said diaphragm to thereby vibrate the diaphragm in definite relation to the movement of the armature, a flared portion

at the end of the said hollow rod which connects with the diaphragm, a connection between the said end of the rod and the diaphragm which consists of a solidified mass of a low temperature cementing material 70 contacting with the flared end of said rod and extending also into contact with the surrounding surface of the diaphragm, a flattened portion provided at the other end of said hollow rod, and means for attaching 75 said flattened portion of the rod to the armature, whereby the bending action of the rod is absorbed in said flattened portion and the stiffness of the rod to lateral vibration is 80 not disadvantageously affected.

3. Sound reproducing apparatus of the class described which comprises a permanent magnet, pole pieces for said magnet forming between them an air gap, an armature of magnetic material mounted for a limited 85 rotational movement through said air gap in magnetic flux transferring relation with said pole pieces, pole faces provided on said pole pieces at the said air gaps of sufficient flux conducting capacity to carry without 90 saturation the maximum quantity of magnetic flux normally required for a satisfactory energy output, the said pole faces and the said armature being of comparable flux carrying capacity, and a sloped portion on 95 said pole pieces constituting a tapered end for the pole pieces terminating at the said pole face and extending back in one direction from said pole face at a relatively sharp 100 angle to the direction of extent of said pole face to form the full section of the pole piece of at least twice the area of the pole face.

4. Sound reproducing apparatus of the class described which comprises a permanent magnet and pole pieces having pole faces of 105 elongated shape and of magnetic flux conducting area somewhat less than the flux conducting area of the said pole pieces back of the pole faces, whereby a flux density in the said pole faces substantially equal to the 110 saturation value for the said pole faces can be used without reaching the saturation point in the said pole pieces back of the pole faces, but of substantial area to carry, without objectionably passing the saturation 115 point, the maximum effective quantity of magnetic flux which will normally pass from the pole pieces during operation of the apparatus in generating, under the conditions normally required of apparatus of its 120 class, that quantity of sound output which is the most advantageous for the listener, and a tilting armature operating in magnetic flux conducting relation with said pole pieces of cross sectional area also 125 of elongated shape and of flux carrying capacity comparable to that of each of said pole faces so that for all positions of tilt normally attained by said armature, due either to reasonable inaccuracies of adjust- 130

ment of the armature into neutral position or to its normal vibrational movement in the generation of sound in satisfactory volume, the magnetic flux therein does not objectionably exceed the saturation value.

5. Sound reproducing apparatus of the class described which comprises a permanent magnet, a pair of pole pieces made up of laminations of magnetic material associated with said permanent magnet, a pair of arm portions provided on each pole piece extending into proximity with corresponding arm portions of the other pole pieces, thus forming air gaps between the adjacent ends of the respective arm portions, pole faces provided at the said adjacent ends of said arm portions extending substantially at right angles to the normal direction of passage of magnetic flux across the air gap between the two pole pieces, a sloped portion provided on the outer face of each of said arms extending back from the pole face so that the flux transmitting area of each of the pole faces is less than the flux carrying cross sectional area of the body portion of the arm back of the pole face, and an armature consisting of a single piece of magnetic material tiltably mounted in the air gaps between the pole pieces in flux conducting relation with said pole faces and having a sizeable cross sectional area sufficiently large to carry, without reaching the saturation point, such quantity of magnetic flux as is necessary to produce a sound volume output commensurate with all reasonable requirements of apparatus of this class, having roughly a one to one ratio of cross sectional area of each of said pole faces, and presenting such cross sectional area as an elongated rectangle so that the armature is in the form of a wide thin strip of width at least several times its thickness.

6. Sound reproducing apparatus of the class described which comprises a permanent magnet with pole pieces forming an air gap between them and sloped toward their ends so that the flux carrying area of each of the pole faces at the air gap is substantial and adequate for a respectably large sound output without magnetic saturation at the pole faces but is less than the flux carrying cross sectional area of the pole pieces back of the said pole faces, and a short, wide, reasonably thin armature of magnetic material mounted for a partial rotative movement in the air gap between the pole pieces of the magnet so that its position with reference to the respective pole faces is different at different positions in its range of movement, and hav-

ing a cross sectional area of the same general order of magnitude as that of the said pole faces so that when the flux in the pole faces is approximately at saturation value the flux in the armature will not substantially exceed the saturation point for all positions of tilt attained during the production of a reasonable required sound output.

7. Sound reproducing apparatus of the class described comprising a permanent magnet having pole pieces with two pole face carrying portions forming air gaps between them, and an armature tiltably movable in said air gaps consisting of a short, wide reasonably thin piece of magnetic material having a substantial total transverse cross sectional area extending at its ends beyond the inner sides of said pole face carrying portions but terminating short of the outer sides of said portions so that the principal pole face area effective in transmitting magnetic flux between the respective pole piece portions and the armature is less than the flux conducting across sectional area of the said portions at a point back of the pole faces but is a substantial area so that when the apparatus is operated with the high flux density in the air gaps between the pole faces and the armature which is required for good efficiency and is operated to deliver the proper sound output commonly required of apparatus of this class to produce the best effect on the listener the said pole faces and the armature are not subject to substantial magnetic saturation.

8. Sound reproducing apparatus of the class described which comprises a permanent magnet having pole pieces arranged so that an air gap is formed between them, pole faces at the said air gaps of sufficiently great magnetic flux conducting capacity as to produce a satisfactory energy output without objectionable saturation, a flat single piece armature mounted for a limited tilting movement in the air gap and having a cross sectional area sufficiently large so that with the armature in the maximum position of tilt normally required for the generation of a sound volume output sufficiently great to satisfy all reasonable demands upon the apparatus and with approximately the maximum effective flux between the said pole faces and the armature that can practicably be attained without passing the magnetic saturation point at any section of the said pole pieces, the flux density in the armature does not substantially pass the saturation point.

BEN E. BROWN.
